UNITED STATES PATENT OFFICE.

REVELEY G. BEATTIE, OF CHAGRIN FALLS, OHIO, ASSIGNOR TO H. W. BEATTIE AND SONS, INC., OF CLEVELAND, OHIO, A CORPORATION OF OHIO.

DESIGN FOR A BADGE OR ARTICLE OF SIMILAR NATURE.

Application filed June 25, 1926. Serial No. 18,187. Term of patent 14 years.

To all whom it may concern:

Be it known that I, REVELEY G. BEATTIE, a citizen of the United States, residing at Chagrin Falls, in the county of Cuyahoga and State of Ohio, have invented a new, original, and ornamental Design for a Badge or Article of Similar Nature, of which the following is a specification, reference being had to the accompanying drawing, forming a part thereof.

In the drawing:

The figure is a plan view of a badge or article of similar nature showing my new design.

I claim:

The ornamental design for a badge or article of similar nature substantially as shown.

In testimony whereof I affix my signature.
REVELEY G. BEATTIE.
